(57) **CLAIM**

The ornamental design for a retail display strap, as shown and described.

DESCRIPTION

FIG. 1 is a front perspective view of a retail display strap showing my new design in an unfolded position;

FIG. 2 is a left side elevation view thereof;

FIG. 3 is a right side elevation view thereof;

FIG. 4 is a front elevation thereof;

FIG. 5 is a rear elevation view thereof;

FIG. 6 is a top plan view thereof;

FIG. 7 is a bottom plan view thereof; and,

FIG. 8 is a rear elevation view of the retail display strap of FIG. 1 in an assembled, folded position.
